Attorney, Agent, or Firm—Bell, Seltzer, Park & Gibson

[57] CLAIM

The ornamental design for a blank for a sock package, substantially as shown and described.

DESCRIPTION

FIG. 1 is a top plan view of a blank for a sock package embodying my new design, the bottom plan view being a mirror image of the view shown; and

FIG. 2 is a side elevational view of the blank for a sock package shown in FIG. 1.

The dashed lines in the drawing represent fold lines.
